UNITED STATES PATENT OFFICE.

JAMES R. MOFFATT AND RALPH S. KELSO, OF CHICAGO, ILLINOIS, ASSIGNEES TO UNION SPECIAL MACHINE COMPANY, OF CHICAGO, ILLINOIS, A CORPORATION OF ILLINOIS.

THREAD-CONTROLLING DEVICE FOR SEWING-MACHINES.

1,071,451.

Specification of Letters Patent

Patented Aug. 26, 1913.

Application filed October 16, 1911. Serial No. 654,865.

To all whom it may concern:

Be it known that we, JAMES R. MOFFATT and RALPH S. KELSO, citizens of the United States, residing at Chicago, in the county of Cook and State of Illinois, have invented certain new and useful Improvements in Thread-Controlling Devices for Sewing Machines, of which the following is a description, reference being had to the accompanying drawing and to the letters and figures of reference marked thereon.

Our invention relates to improvements in sewing machines, and particularly to a thread-controlling device therefor. It has been designed especially for use in connection with the Union Special Side Wheel Cylinder Machine, such as illustrated in United States Patent No. 583,415, granted May 25, 1897, and is more especially adapted for machines of this character used for the manufacture of high grade shirts. Manufacturers of these shirts use a very fine thread, and in removing the work, the looper thread sometimes breaks, because it is clamped by the nipper springs. The use of a fine looper thread is desirable, because it improves the appearance of the seam, and reduces any tendency to make an unsightly ridge.

The invention consists in the matter hereinafter described and referred to in the appended claims.

The invention is illustrated in the accompanying drawings, in which—

Figure 1 is a side view of a side wheel cylinder sewing machine embodying our invention; Fig. 2 is a plan view; Fig. 3 is a diagrammatic view, illustrating the tension-releasing devices and operating means therefor; and Fig. 4 is a detail view of the nipper springs, together with a view of the finger 19 operating the upper one of said springs, the two positions of the finger and upper nipper spring being shown respectively in full and dotted lines.

In these drawings, the machine as a whole is of the type shown in the above mentioned patent, and is marked 1. It has the presser foot 2, presser bar 3, presser bar lever 4, needle-thread tensions 5, looper thread tensions 6, and upper and lower nipper springs 7, 8, all of the usual construction.

The nipper springs 7 and 8 are caused to grip the thread by a rotating cam 8^a carried

by the main shaft in the manner well known in this type of machine. This cam is formed with one flat or cut-away side, so that the springs are intermittently operated to grip the thread.

Connected at one end to the presser bar lever by the adjustable plate 9, is a bell crank lever 10, pivoted on the machine frame at 11, and carrying at its other end the arm 12, having two (or as many as may be needed) fingers 13, adapted to enter between the needle thread tension disks and separate them, when the lever 4 is drawn down to raise the presser foot. Connected to the forward arm of the bell crank lever 10 is a rod 14, which at its inner end has an opening to receive the end of a vertical rod 15, normally spring pressed downwardly by the spring 16. This rod is guided by the clips 17, which are secured to the machine frame. Adjacent the lower end, this rod has an arm 18, formed, as shown, at its outer end with a vertical arm 19, which in the upward movement of the rod 15 engages the upper nipper spring 7 and forces it upward to release the looper thread. Attached to this arm 18 is the arm 20, having the two fingers 21 to engage and open the tension disks 6. The parts are so timed that when the presser bar lever 4 is drawn down, the bell crank lever 10 swings, releasing the needle thread tension disks, and simultaneously the rod 15 is raised vertically and the looper thread tensions and nipper springs also released from pressure on the thread, so that when the presser foot is raised from the work for the purpose of removing the material, all strain on both threads is relieved.

From the above description it will be apparent that the cam for closing the nipper springs 7 and 8 engages the lower spring 8, while the manually operated device 19 engages the upper spring 7, and, therefore, the nipper springs may be separated, although the cam is in position, to cause said springs to grip the thread.

It will be understood that parts not herein described are of usual well known construction, and that while we have shown two looper threads and two needle threads, and the consequent number of tensions, one or more may be used.

Having thus described our invention, what

- we claim as new and desire to secure by Letters Patent, is:—
1. In a sewing machine having thread controlling devices, including coöperating members for nipping the thread, means engaging one of the members for causing the same to nip the thread, and manually operated means for engaging the other member to move the same to release the thread.
  2. In a sewing machine having thread controlling devices, including coöperating nipping springs, a cam engaging one of said springs for moving the same to nip the thread, and manually operated means for engaging the other spring for moving the same to release the thread.
  3. In a sewing machine having thread-controlling devices including a tension device and an intermittent thread-nipping device acting on the same thread as the tension device, means manually controlled by the operator for simultaneously releasing the tension and nipping devices.
  4. In a sewing machine having thread-controlling devices including needle thread tensions, looper thread tensions, and an intermittently acting nipping device, and means for simultaneously releasing all said devices at the will of the operator.
  5. In a sewing machine having thread-controlling devices including needle thread tensions, looper thread tensions, and an intermittently acting nipping device for the looper thread, means for simultaneously releasing all of said devices at the will of the operator.
  6. In a sewing machine having thread-controlling devices including needle thread tensions, looper thread tensions, and a simultaneously acting nipping device for the looper thread, a presser foot, and means for simultaneously releasing the needle and looper thread tensions and the nipping device, as the presser foot is raised.
  7. In a sewing machine having thread-controlling devices including needle thread tensions, looper thread tensions, and an intermittently acting nipping device for the looper thread, and a single lever controlled by the operator for releasing all of said devices simultaneously.
  8. In a sewing machine having thread-controlling devices including needle thread tensions, looper thread tensions, and an intermittently acting nipping device for the looper thread, a presser foot, and a single lever controlled by the operator for simultaneously raising the presser foot and releasing all of said devices.

In testimony whereof we affix our signatures, in presence of two witnesses.

JAMES R. MOFFATT.
RALPH S. KELSO.
